GUN CHARGER

James E. Chapman, Los Angeles, Calif., assignor
to North American Aviation, Inc., Inglewood,
Calif., a corporation of Delaware

Application December 17, 1941, Serial No. 423,355

5 Claims.

(Cl. 89—1)

The present invention relates generally to machine guns and more particularly to the charging of the gun to feed thereto another shell in the event of failure of the previous shell to fire, there being in such an instance no recoil of the charging mechanism to effect gun-actuated feed of a new shell as there is in ordinary continuous firing.

In guns of small calibre the charging bolt may be readily drawn back by hand and a new shell fed into the gun before release of the bolt so it may move to charging position under the actuation of its spring which is placed under compression when the bolt is drawn back. However, in guns of larger calibre, such, for instance, as fifty calibre guns now preferred in airplanes, the charging spring is of such strength that it is impractical for the bolt to be drawn back by hand.

It is the primary object of this invention to shift the gun bolt back, or retract the same from charging position by spring retracting means of a strength substantially greater than the strength of its charging spring, thus placing the latter under compression during retraction of the bolt, and to then release the bolt at the end of its retracting movement, for forward or charging movement under its own charging spring.

It is a further object to normally hold the spring retracting means in a compressed condition at all times and to automatically release the same, for action within a predetermined interval or period after failure of the gun to fire, by an electrical control means which will function to recompress the spring retracting means, after retraction and release of the gun bolt, so that said means will be restored to a condition ready for again operating to the desired end in the event of a subsequent failure of the gun to fire.

The invention, therefore, contemplates an automatic electrical power and control for the entire cycle of charging a new shell whenever a shell fails to fire. This automatic retraction of the gun bolt operates the usual means of discharging the previous shell and feeding a new shell into the chamber of the gun.

It is to accomplish the foregoing in a practical effective manner that there is suggested the means to be now described in detail, as to construction and assembly, as well as operation, reference being made in such description to the accompanying drawing which forms a part of this specification, and in which,

Fig. 1 is a top plan view showing the mechanism of the present invention assembled on a

gun, the parts being in the normal position ready for operation.

Fig. 2 is a side view thereof.

Fig. 3 is a detail horizontal sectional view on an enlarged scale, showing the normally latched portions of the rack, the dog-carrying spring crosshead.

Fig. 4 is a diagram illustrating the electrical control and operating connections.

Fig. 5 is a fragmentary vertical sectional view through portions of the spring holders and the spring actuated crosshead.

Referring now particularly to Figs. 1 and 2, there is shown a pair of vertically spaced parallel longitudinal spring holding tubes 10 and 11 mounted, as by means of a supporting bracket, including end members 12 and 13 at the forward and rear ends of the tubular holders, at one side of a machine gun 14 so that the gun bolt 15 is opposite the space between the holders and in its forward, or gun charging position, is intermediate of the ends of the tubes.

The tubular holders 10 and 11 have facing longitudinal slots through which the laterally extending end portions 16 of a crosshead 17 project to form abutments for the rear ends of springs 18 housed by the tubes with their forward ends abutting the forward closed ends of the tubes. Thus the springs 18 are compressed by forward movement of the crosshead 17 and, when the crosshead is free to move rearwardly, the springs exert their combined strength to effect such movement. The combined strength of springs 18, it may be said at this point, is substantially greater than the strength of the recoil spring of the gun charging mechanism, the latter spring being indicated at 19.

It is understood that the laterally projecting gun bolt 15 is a part of the gun charging mechanism and that in normal gun operation, it is the recoil after firing that shifts the bolt 15 rearwardly, placing recoil spring 19 under compression for shifting the charging mechanism and its bolt 15 forwardly, and that during this movement the shell previously fired is discharged and a new shell fed into the gun for the next firing operation. When a shell fails to fire there is no recoil and hence no charging operation, and in guns of greater than thirty calibre it is impractical to pull the gun bolt 15 rearwardly by hand against the tension, which is necessary in such guns, of the recoil spring 19.

According to the present invention, the crosshead 17 is normally latched in a position forwardly of the forward charging position of the

gun bolt. In this position, the crosshead is controlled by means which automatically become active upon failure of the gun to fire, for the purpose of releasing the crosshead so that it will engage the gun bolt 15 and shift the latter rearwardly or retract the same under compression of the springs 18. In such movement the recoil spring 19 is placed under compression and at the end of the retractile movement of the gun bolt 15, the crosshead 17 automatically releases therefrom to thus permit the recoil spring 19 to again shift the charging bolt to forward position, accomplishing by spring means what ordinarily results from recoil in the gun.

The invention controls, by electrical means, the release of the crosshead after a predetermined interval following failure of the gun to fire, and also provides for the forward return of the crosshead 17 after release from the gun bolt, to again place its actuating springs 18 under compression and once again set the parts in a normal latched position ready for effective operation when the gun fails to fire.

In order to engage the gun bolt 15, the crosshead 17 is provided upon its inner surface opposing the gun 14, with a pivoted, vertically swinging dog 20. This dog has an upper engaging nose 21 and a rearwardly and downwardly inclined tail 22. A stationary block 23 is positioned on the supporting bracket of the spring holders 10 and 11, at approximately the forward limit of movement of the crosshead 17 and when the tail 22 of the dog 20 rides on this block, its nose is lifted, forwardly of the gun bolt 15, in the forward charging position of the latter. Thus when the crosshead is released, the nose 21 of dog 20 engages the bolt and the latter will be moved rearwardly with the crosshead since the latter moves in a path coinciding with the path of retractile movement of the bolt, though it is understood the actual position of the crosshead itself is slightly beyond the free end of the bolt.

At the rear end of the tubular holders 10 and 11, the rear end piece 13 of the supporting bracket has a projecting pin 24 as seen in Figure 2, and when the crosshead 17, carrying the bolt 15 rearwardly as above, reaches the end of its rearward movement, the tail 22 of dog 20 rides under pin 24 and is thus shifted downwardly to withdraw its nose 21 from in front of the gun bolt 15. Thus the gun bolt is released for forward movement under the effect of its compressed recoil spring 19.

It will be noted in Figs. 3 and 5 that the crosshead 17 has upper and lower recesses 20a facing the dog 20 and that the latter has a spring pressed latch ball 17a. Thus the dog will be held in either its upper or lower position, until shifted by the block 23 or pin 24.

The latch which normally holds the cross head 17 in forward position is shown in Fig. 3 as of the shape of a bifurcated bell-crank 25, pivoted intermediate its ends at 26 on the upper and lower surfaces of an elongated rack member 27 at the rear end of the latter. The rearwardly extending latch arm 28 of latch member 25 substantially parallels the rack bar 27 and has at its rear end an inturned nose 29, so that it may ride along the outer face of the crosshead 17 and engage the rear edge of the latter in latched position, as shown in Fig. 3. The upper and lower arms 30 of latch member 25 extend at an angle forwardly and inwardly and have similarly extending slots 31, in the lower rear end of which a vertical pin 32 is normally held by a leaf spring 33 anchored at 34 on the inner surface of the rack bar 27.

There is also supported on the bracket in connection with, and extending above, the tubular spring holders 10 and 11, a motor 35, the housing of which encloses a reduction gear for its depending driven shaft 36. This shaft extends vertically, downwardly and carries on its lower end a pinion 37 in mesh with the teeth 38 along the outer face of the rack bar 27. Also on the shaft 36 there are fixed cams 39 above and below the rack bar 27 which, when rotated by rotation of said shaft, engage at their ends with the upper and lower ends of pin 32. It will be observed that when pinion 37 and its shaft 36 are rotated clockwise in Fig. 3 to cause initial rearward movement of rack bar 27, the cams acting against pin 32 in its lowermost position, will shift the latch arms 30 rearwardly and, since the latch member is, in effect, a bell-crank, will force the latch arm 28 laterally to free the same from, and release the crosshead 17. This is what initially takes place when the motor 35 is first energized upon failure of the gun to fire and hence the before-described movements take place following release of the crosshead. The rack bar follows rearwardly during such movements and at the rear end of its rearward stroke it encounters the crosshead after the latter has released the gun bolt, and the latch member 25 slides into re-engagement with the crosshead.

At this time, motor 35 is reversed and the rack bar 27 is then shifted forwardly to its normal position of rest. Toward the end of this movement the rotating cams 39 merely shift the pin 32 in the slots 31 of the latch member against the tension of spring 33 without tending to shift the position of the latch member and hence the crosshead continues to follow the rack bar in its forward movement and remains in latched connection therewith after the rack bar has completed its return movement and motor 35 is de-energized. During this movement the springs 18 are again placed under compression and thus all parts are restored to position ready for a subsequent operation.

The electrical control of the motor 35 is in accordance with the diagram of Fig. 4 wherein the motor is shown as a split field reversible type. According to the diagram, current is available to the controlling circuits from a source of current 40, whenever the main switch 41, or firing key, is closed for supplying current to the gun firing solenoid line 47. A time delay relay switch 43 remains inactive as long as current is normally utilized in the firing of the gun. In the brief intervals between normal firing of the gun, the gun bolt 15 momentarily closes the switch 48. The remainder of the time the switch 48 is open. This momentary closing of the switch 48 closes the following circuit: source 40, wire 74, resistance 73, wire 44, switch 48, wire 56, switch 54 and its ground. During momentary closing of this switch 48 which is at the time the gun bolt is in its forward or charging position, the resistance 73 does not heat up sufficiently to close said contacts of the relay 43. However, when the gun fails to fire, the gun bolt 48 maintains the switch 48 closed, thus permitting the resistance 73 to continue to heat up. The resistance 73 is sufficiently close to the spaced contacts of the relay 43, to heat such contacts when the resistance 73 becomes heated. When the spaced contacts of the relay 43 become heated to a predetermined point, they contact each other, thus closing the last-described circuit. When said contacts engage each other, they complete a circuit from

the source 40, through wires 14, 46, 45 and 56 and through switch 54 to its ground, for energizing an electro-magnet 47.

When electro-magnet 47 is thus energized it draws armatures 49 and 50, respectively, against contacts 51 and 52, contact 51 being connected to feed line 53, and contact 52 being grounded. A grounded reversing switch 54 is shown in the starting position, and a holding circuit is thus formed from feed line 53, through contact 51, armature 49, wire 55, wire 46, electro-magnet 47, wire 45, wire 56 and reversing switch 54 to ground. At the same time current flows from feed line 53 through motor 35 and its field 57, in the direction of arrow 58, wire 59, armature 50, and contact 52 to ground, so that the motor operates in a direction to shift the rack bar 27 rearwardly and initially release the crosshead for rearward movement to retract the gun bolt 15. As soon as the gun bolt starts rearwardly the switch 48 is permitted to open, thus breaking the time delay relay circuit.

The rack bar 27 is thus moved rearwardly to re-engage the crosshead until a projection 60 adjacent the forward end of rack bar engages reversing switch 54 and shifts the same from contact with wire 56 to contact with wire 61. In thus shifting the reversing switch, the holding circuit is broken, armatures 49 and 50 return to their normal positions, and the motor circuit through field 57 is broken. In the reversed position of switch 54, however, current flows from the feed line 53, through motor 35, and its field 62, in the direction of arrow 63, wire 61 and switch 54 to ground, thus reversing the motor and causing the return, forward movement of rack bar 27, with the re-latched crosshead 17, to normal forward position. As such position is reached, a projection 64 at the rear end of the rack bar engages and shifts the reversing switch 54 back to contact with wire 56 so that the motor stops and the parts are thus restored to the normal forward latched position ready for a further operation any time the gun fails to fire.

In thus providing for retraction of the charging mechanism of the gun in an entirely automatic manner involving the use of springs for bringing about retraction of the gun bolt, it is plain that the invention imparts to the charging mechanism a movement which very closely approaches its movement under recoil in normal gun operation.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. An electrically controlled bolt retracting mechanism for machine guns, comprising a frame, a bolt retracting member movably mounted for reciprocation on said frame and adapted to be positioned forwardly of the path of reciprocation of the gun bolt during normal gun operation, said member including means engageable with the bolt, spring means connected between said frame and said member to actuate said member for bolt retracting movement, said spring disposed on said frame to be recompressed by said member during the return of said member to its forward position, means positioned on said frame in the path

of reciprocation of said member to disengage said bolt engaging means from the bolt at the end of bolt retracting movement, and electrically controlled means positioned on said frame to hold said member in its forward position, said electrically controlled means including means to release said member for bolt retraction and means to return said member to its forward position.

2. An electrically controlled bolt retracting mechanism for machine guns, comprising a frame, a bolt retracting member movably mounted for reciprocation on said frame and adapted to be positioned forwardly of the path of reciprocation of the gun bolt during normal gun operation, said member including means engageable with the bolt, spring means connected between said frame and said member to actuate said member for bolt retracting movement, and having a force exceeding the compressed force of the recoil spring of the gun bolt, said spring disposed on said frame to be recompressed by said member during the return of said member to its forward position, means positioned on said frame in the path of reciprocation of said member to disengage said bolt engaging means from the bolt at the end of bolt retracting movement, and electrically controlled means positioned on said frame to hold said member in its forward position, said electrically controlled means including cam means to release said member for bolt retraction and means to return said member to its forward latch held position.

3. An electrically controlled bolt retracting mechanism for machine guns, comprising a frame, a bolt retracting member movably mounted for reciprocation on said frame and adapted to be positioned forwardly of the path of reciprocation of the gun bolt during normal gun operation, said member including means engageable with the bolt, spring means of greater strength than the recoil spring of the gun both connected between said frame and said member to actuate said member for bolt retracting movement, means for normally maintaining said spring under compression, means positioned on said frame to disengage said bolt engaging means from the bolt at the end of bolt retracting movement, and electrically controlled means positioned on said frame to hold said member in its forward position, said electrically controlled means including means to release said member for bolt retraction upon failure of the gun to fire and means to return said member to its forward position.

4. An electrically controlled bolt retracting mechanism for machine guns, comprising a frame, a bolt retracting member oscillatably mounted on said frame a latch for holding a bolt retracting member in non-effective position during normal gun operation, said bolt retracting member including means engageable with the bolt upon release of the latch, spring means connected between said frame and said member to actuate said member for bolt retracting movement, said spring disposed on said frame to be recompressed by said member during the return of said member to its latched position, means on said frame to disengage said bolt engaging means from the bolt at the end of bolt retracting movement, and electrically controlled means positioned on said frame to hold said bolt retracting member to its latched position, said electrically controlled means including means to actuate the latch to release said member for bolt retraction and means to return said member to its latched position.

5. An electrically controlled and actuated bolt retracting mechanism for machine guns, com-

prising a frame, a bolt retracting crosshead movably mounted for reciprocation on said frame and having releasable means engageable with the bolt for retracting the bolt, spring means connected between said frame and said crosshead to actuate said crosshead for bolt retracting movement, said spring disposed on said frame to be recompressed by said crosshead during movement of said crosshead reversely to its bolt retracting movement, means positioned on said frame in the path of reciprocation of said crosshead to disengage said

5 bolt engaging means from the bolt at the end of bolt retracting movement, and electrically controlled and actuated means positioned on said frame including a latch to render said crosshead non-effective, said electrically controlled means including a cam constructed and arranged to release said crosshead from said latch for bolt retraction and means to return said crosshead to its non-effective latched position.
